(57) **CLAIM**

I claim the ornamental design for a telescoping mini reading light, as shown and described.

DESCRIPTION

FIG. 1 is a top view of the telescoping mini reading light showing my new design having a telescoping arm with a pivoting light at its end, in a fully stored position;

FIG. 2 is a left side view thereof;

FIG. 3 is a front view thereof;

FIG. 4 is a right side view thereof;

FIG. 5 is a back view thereof;

FIG. 6 is a bottom view thereof;

FIG. 7 is a perspective view thereof;

FIG. 8 is a top view of the telescoping mini reading light with the telescoping arm and the light in a fully extended position;

FIG. 9 is a left side view thereof;

FIG. 10 is a front view thereof;

FIG. 11 is a right side view thereof;

FIG. 12 is a back view thereof;

FIG. 13 is a bottom view thereof;

FIG. 14 is a front perspective view thereof; and,

FIG. 15 is a back perspective view thereof.
